UNITED STATES PATENT OFFICE.

FREDERICK SPITZ, OF NEW YORK, ASSIGNOR OF ONE-HALF TO THOMAS C. BOOTH, OF LARCHMONT, NEW YORK.

GARMENT-HOOK.

SPECIFICATION forming part of Letters Patent No. 533,677, dated February 5, 1895.

Application filed September 21, 1894. Serial No. 523,692. (No model.)

To all whom it may concern:

Be it known that I, FREDERICK SPITZ, of New York city, New York, have invented an Improved Garment-Hook, of which the following is a specification.

This invention relates to a garment hook more particularly designed to be attached to a waistband in such a manner that it may be readily removed and replaced when the garment is to be washed.

In the accompanying drawings Figure 1 is a perspective view of a waistband provided with my improved hook. Fig. 2 is a perspective view of the hook, Fig. 3 a rear view thereof, and Fig. 4 a further perspective view of the hook.

The hook A is composed of a single length of wire, which is bent to form the head, shank and eyes, all of which are designated by different letters of reference.

At one end the hook is provided with a flat bar a, from the ends of which the wire is turned downward and inward to form a flattened or laterally expanded head a'. The shank extends downward from the head, and is then bent first upward and then again downward, so as to form within itself two hooks a², a³. At the end of the shank, the wire is bent sidewise and upward to form one large continuous loop a⁴, which is by the rear section of the shank divided into the two eyes b. The loop a⁴, should be provided with

a central indentation a⁵, the lower point of which meets the second bend a³, of the hook shank, and prevents the tape drawn through 35 the eyes b, from slipping out of such eyes and into the bend a².

The waistband or other article B to which the hooks are to be secured is provided with the button holes c, placed in an upright position as shown.

The hooks A are all strung upon a common tape E, which is passed through the eyes b, and may be engaged by projections a⁶, of the hook-shank, which retain the hooks in position. Next the hooks are passed with their heads a', through the button holes c, up to the second bend a³, upon which the hooks remain suspended. The hooks are now in their proper working position, and may be used in 45 the ordinary manner by slipping their elongated heads into the button holes of the garments which are to be attached to the waistband.

What I claim is—

A garment hook formed of wire, having a doubly bent shank, a head upon the hook-tongue proper, and a clamping portion formed by a loop bent up against the shank, substantially as specified.

FREDERICK SPITZ.
